UNITED STATES PATENT OFFICE

2,598,473

ELECTRIC OSCILLATION GENERATOR

Arthur Richard Warner, London, and Derrick Arnott Ward, Beddington, England

Application October 7, 1949, Serial No. 120,014
In Great Britain March 1, 1949

5 Claims. (Cl. 250—36)

1

This invention relates to electric oscillation generators, and is primarily concerned with the provision of means for cyclically increasing the output of a power oscillator gradually from a low or zero output to a substantially greater output. Such an oscillation generator finds application in the operation of gas discharge tubes for advertising and other purposes, in which the discharge in the tube is caused to increase gradually along the tube, then to be extinguished, and to repeat the operation cyclically. Such an arrangement is described, for example, in British Patents No. 399,566 and 423,362.

According to the present invention there is provided a valve oscillator stage, to which is applied a control voltage derived from a sawtooth voltage generator, the sawtooth generator comprising a capacitance adapted to be slowly charged through a resistance or the equivalent of a resistance, such as a valve and discharged rapidly by a valve arranged as a blocking oscillator. Preferably the power oscillator stage makes use of a valve or valves of the screen-grid type, the potential of the screen being varied for control purposes, and in this case the sawtooth generator feeds the screen of the power oscillator through a cathode follower stage.

One arrangement of an electric oscillation generator in accordance with the present invention will now be described, with reference to the accompanying drawing, the oscillation generator in this arrangement being adapted to supply power for the operation of a gas discharge tube in the manner described above.

The drawing shows the oscillation generator, comprising an oscillator stage 1, and a sawtooth generator stage 2, and the gas discharge tube circuit 3, each shown within a rectangle bounded by broken lines.

The oscillator stage 1 has two power tetrode valves V₂ and V₄ connected as a class "C" push-pull oscillator. The anodes A₃ and A₄ of the valves V₃ and V₄ respectively are coupled to opposite ends of a coil L₁ to the centre point 4 of which the anode supply is connected from the positive terminal B+ of a conventional high tension supply, the negative terminal of which is grounded. The necessary positive feed-back to the control grids CG₃ and CG₄ of the valves V₃ and V₄ is obtained by connecting them through blocking capacitors C₈ and C₉ to appropriate taps 6 and 7 upon the coil L₁. Grid bias is applied to the valves V₃ and V₄ by means of grid leak resistors R₇ and R₈.

The gas discharge tube 3, which is shown sym-

bolically only, is coupled to the oscillator stage 1 by a transformer T₂ and coil L₂ which is coupled to the tank coil L₂. The arrangement is such that if the oscillator output is increased gradually from a low value the discharge will spread gradually from the non-grounded electrode E₁ towards the grounded electrode E₂ and at an appropriate value of oscillator output will extend throughout the tube. If the oscillator output is then reduced sharply to the original low value, which may be zero, the discharge will be extinguished. Thus as described in the aforementioned Patent No. 399,566 the tube may, for example, be in the form of a word so that the extension of the discharge gives the effect of the word being written.

The potential upon the screen-grids SG₃ and SG₄, which are effectively connected together, is controlled by a sawtotooth generator stage 2. This stage, in this particular embodiment of the invention, uses two triode valves V₁ and V₂, which are shown as the two parts of a multiple valve. The valve V₁ is arranged as a cathode-follower type of circuit to provide an output voltage which is applied to the screen grids SG₃ and SG₄ of the oscillator valves to control the oscillator output.

The valve V₂ is arranged as a squegging or blocking oscillator serving periodically to discharge a capacitor in the grid circuit of the first valve.

The valve V₁ includes in its cathode circuit two serially connected resistors R₁ and R₂, which are shunted by a by-pass capacitor C₃. The resistor R₂ is shunted by a capacitor C₂, while a second capacitor, C₁, is connected between the grid CG₁ of the valve V₁ and the upper terminal of the capacitor C₂. Values are given to capacitors C₁ and C₂, and resistors R₁ and R₂ such that the ratio R₁/R₂ is less than the ratio C₁/C₂. A grid resistor R₃ is connected between the grid CG₁ and the cathode K₁ of the valve V₁; the resistor R₃ has a value substantially higher than the resistors R₁ and R₂.

The valve V₂ is arranged as a blocking oscillator and to this end the valve V₂ is tightly coupled, by means of a low frequency transformer T₁, between its grid and cathode circuits, the grid circuit including a biasing resistor R₅ in parallel with a capacitor C₆, the time constant of which is high, in the usual manner. The grid circuit winding of the transformer T₁ is shunted by a capacitor C₄ which determines the frequency of oscillation, and also limits the peak voltage developed.

The anode A₂ of the valve V₂ is connected to the

grid CG₁ of the valve V₁ and hence also to one terminal of capacitor C₁. In known manner, the valve V₂ periodically oscillates so as to produce a large pulse of anode current; a positive voltage appearing at the grid CG₂ of the valve V₂ develops grid current which charges the capacitor C₆ negatively and accordingly makes the grid CG₂ negative. The positive voltage appearing at grid CG₂ is the positive grid voltage which inherently occurs in blocking oscillators due to transformer coupling. The current taken by valve V₂ is taken from capacitor C₁ which is charged through valve V₁. As a result, valve V₂ will discharge the capacitor. The aforementioned negative bias of grid CG₂ due to the negative charge of capacitor C₆ suppresses the anode current until such time as the negative charge on the grid capacitor C₆ leaks away and the cycle of operation is repeated.

When the pulse of anode current is produced in the valve V₂ the grid CG₁ of the valve V₁ is made highly negative, and the anode current of the valve V₁ is suppressed. For a period depending upon the circuit constants the anode current remains suppressed and then recommences, increasing slowly to a maximum value. Eventually the valve V₂ again passes its pulse of anode current and the cycle is repeated. In this way a sawtooth voltage is developed across the resistors R₁ and R₂ which is applied through the non-linear resistance element M₂ to the screen grids SG₃ and SG₄ of the valves V₃ and V₄. The effect of applying this voltage to the screen grids SG₃ and SG₄ is to give a steadily rising oscillator output which is cut off sharply at its maximum. The purpose of the non-linear resistance element M₂ and the capacitor C₅ is to provide a negative bias on the screen grids SG₃ and SG₄ where a negative bias is necessary to reduce the oscillator output to zero. With some valves a negative bias may not be necessary in which case the element M₂ and capacitor C₅ may be omitted. The negative bias is produced owing to the fact that when the sawtooth stage output falls to zero, the voltage previously built up across the capacitor C₅ applies a negative bias to the screen grids SG₃ and SG₄. The charge across the capacitor C₅ leaks away slowly through M₂ which presents a high resistance to the discharge of capacitor C₅.

With this very brief description of the operation of the circuit it is not possible to perceive at once the advantages of the present invention and the following, more detailed, consideration of the circuit is therefore given.

In the first place the operation of the circuit will be easier to understand if values are ascribed to the essential capacitors and resistors. In one example, capacitors C₁ and C₂ were each .5 mfd. resistors R₁, R₂ and R₃ were respectively 33 kilohms, 100 kilohms and 4 megohms. It will be understood that these values are illustrative only.

Starting with the condition where the valve V₂ is just about to pass anode current, the valve V₁ is passing anode current; the valve V₁ is biased only by grid current passing through the grid resistor R₃. The cathode K₁ of the valve V₁ is therefore at a high potential to ground, due to the voltage drop in the load in parallel with the cathode resistors R₁ and R₂, and the potential applied to the screen grids SG₃ and SG₄ of the valves V₃ and V₄ is at, or approaching, the maximum.

The potential across capacitor C₁, due to the potential drop caused by the current passing

10 through resistor R₁ will be about one-third of that across capacitor C₂, due to the drop across resistor R₂.

When the valve V₂ passes anode current the valve V₂ presents in effect a low value of impedance across the two serially connected capacitors C₁ and C₂; the upper plate of the capacitor C₁, and with it the grid CG₁ of the valve V₁, is thereby reduced extremely rapidly to almost zero potential. As the cathode K₁ of the valve V₁ is positive, the valve V₁ is driven rapidly far beyond cut-off and the anode current ceases. The potential of the junction point of capacitors C₁ and C₂ at this time is at a moderately high, positive potential. Because of this, capacitor C₁ receives a charge from capacitor C₂ which is in reverse direction to that previously applied to capacitor C₁ and both capacitors then begin to discharge, capacitor C₁ through resistors R₁ and R₃, and capacitor C₂ through resistor R₂. It should be emphasized that the relatively rapid discharge of capacitor C₁ followed by its charge to a high potential of opposite polarity means that the grid CG₁ of valve V₁ is biased well beyond anode current cut-off. As explained hereafter the period during which the bias remains beyond the cut-off valve determines the period during which the gas discharge tube is extinguished. The time constant of the circuit including capacitor C₂ and resistor R₂ is relatively small and the discharge of capacitor C₂ has no effect upon the anode current of the valve V₁ at this stage. The time constant of the circuit including capacitor C₁ and resistors R₁ and R₃ is relatively high, being of the order of two seconds. Moreover, since resistor R₃ is substantially greater than resistor R₁ a large proportion of the potential difference appearing across capacitor C₁ is applied to the grid CG₁ of the valve V₁ as a negative bias, which prevents the flow of anode current.

As capacitor C₁ discharges via, R₃ and R₁, this negative bias gradually decreases until the point of anode current cut-off is reached and anode current then begins to flow. Up to this point the potential of the screen grids SG₃ and SG₄, of the valves V₃ and V₄ is such that the oscillator output is zero and the gas discharge tube is completely extinguished. When the anode current begins to flow in valve V₁ the current through R₁ reverses, but not that through R₃. The discharge of capacitor C₁ is maintained, but now the discharge current flows through the valve V₁ instead of through R₁. Eventually C₁ is completely discharged and commences to recharge with opposite polarity reaching the condition described above just prior to the passage of anode current through the valve.

Thus, the anode current of the valve V₁ gradually increases, producing the desired sawtooth output across the resistors R₁ and R₂.

As soon as anode current commences in the valve V₁, there is produced a potential drop across resistor R₂, and capacitor C₂ is charged accordingly. As the anode current increases the potentials across the capacitors C₁ and C₂ increase until they attain the limiting values determined by the voltage drops across resistors R₁ and R₂. At about this point the cycle of operation is repeated.

It will be seen that the ratio of the values of resistors R₁ and R₂ determines, in part, the potential to which capacitor C₁ is charged when the valve V₂ is about to take current and therefore the potential to which capacitor C₁ is

charged in the reverse direction when the valve V_2 takes current. The ratio R_1/R_2 can thus be varied to control the "off" period of the oscillator stage. This "off" period is also controlled in part by the value of resistor R_3 , but this resistor, affecting the time constant of the discharge circuit for capacitor C_1 , has the more important effect of controlling the slope, or rate of increase, of the sawtooth wave which is produced. This slope can be made relatively linear, so that the speed of extension of the discharge can be made relatively constant. The total cycle time is controllable by the time constant of the grid bias circuit of the valve V_2 .

It will be seen, therefore, that the present invention permits control of the power oscillator so as to control the "off" period of the tube, the speed of the extension of the discharge, that is the speed of "writing" where it is a word sign, and the cycle time of the discharges. It is also possible to control the slope of the trailing edges of the sawtooth waves, by means of an additional time constant circuit composed by an additional resistor connected between the junction of the resistor R_3 with the lead to the anode A_2 of the valve V_2 , and the grid CG_1 of the valve V_1 and an additional capacitor connected between the grid CG_1 and the junction of the capacitors C_1 and C_2 .

The cathode resistor R_1 may, as shown, be shunted by a non-linear resistance element M_1 in series with a resistor R_4 to linearise the charging voltage of the capacitor C_1 . Although in the above arrangement a blocking oscillator has been provided for controlling the cycle of operation of the sawtooth generator, it will be understood that other suitable devices may be used for this purpose.

Where it is desired to operate several discharge tubes in this manner each with its own oscillator it is only necessary to provide one blocking oscillator or like discharge means to control the sawtooth generator of each oscillator. Alternatively, each discharge tube may be provided with its own complete oscillation generator including sawtooth generator and blocking oscillator, and by suitable interconnection one blocking oscillator may be used to trigger the remaining blocking oscillators so that operation of all the discharge tubes is synchronised.

What is claimed is:

1. An electric oscillation generator comprising in combination a valve oscillator stage, a sawtooth waveform generator, said sawtooth waveform generator comprising a capacitance, means for varying the charge on said capacitance relatively slowly by discharging it from a condition of predetermined charge and polarity and recharging it with opposite polarity, and means for discharging said capacitance and recharging it with opposite polarity to said condition relatively rapidly, an impedance across which the output of said sawtooth waveform generator is developed and means the potential of which controls the output of said oscillator stage connected to said impedance.

2. In an electric oscillation generator, at least one multi-electrode oscillator valve connected in regenerative circuit, a sawtooth wave-form generator comprising a capacitance, means for varying the charge on said capacitance relatively

slowly from a charge of one polarity to a charge of opposite polarity, a blocking oscillator for discharging said capacitance from said charge of opposite polarity relatively quickly, means for charging said capacitance relatively quickly to said charge of one polarity, and means for applying the output voltage of said sawtooth waveform generator to an electrode of said oscillator valve for controlling the oscillatory output thereof.

3. In combination, oscillatory means for generating high frequency oscillations, means for generating a sawtooth waveform voltage comprising a capacitance, means for varying the charge of said capacitance relatively slowly from a charge of one polarity to a charge of opposite polarity, means for varying the charge of said capacitance relatively quickly from said charge of opposite polarity to said charge of one polarity, and means for applying said voltage to said oscillatory means to control the power output thereof.

4. In combination, an electrical oscillator, said electrical oscillator comprising two tetrode valves connected in push-pull relationship with their screen grids commoned, a cathode-follower valve stage comprising a valve, two series resistors in the cathode lead of said valve, a third resistor in the grid-cathode circuit of said valve, and two series capacitors in shunt with the three resistors, the junction of said two capacitors being connected to the junction of said two cathode lead resistors, a blocking oscillator valve circuit, the anode-cathode path of which is connected in shunt with said two capacitors for periodically presenting a low impedance path across said capacitors, and a connection from the cathode of said cathode follower valve to said commoned screen grids for applying the voltage developed across said two series resistors thereto.

5. In a gas discharge tube control circuit; a valve oscillator source of high frequency oscillations adapted to be connected between the electrodes of said gas discharge tube; a valve for said valve oscillator source having anode, cathode and at least one grid for controlling the power output of said source; a capacitor; valve means for charging said capacitor, said capacitor being connected in anode current controlling relationship to said valve means; resistance means in the cathode circuit of said valve means; a blocking oscillator connected to said capacitor for periodic discharge thereof at an appreciably quicker rate than the rate of charge thereof; and means for applying the voltage developed across said resistance means to the grid of the valve of said valve oscillator source.
